(57) **CLAIM**

The ornamental design for a plastic food container comprising a base and lid, as shown and described.

DESCRIPTION

FIG. 1 is a front perspective view of a plastic food container comprising a base and lid (the base having the lid secured thereon) showing the new design;

FIG. 2 is an angled front perspective view of the bottom thereof (the base having the lid secured thereon);

FIG. 3 is a front elevation view thereof (the base having the lid secured thereon), the rear elevation view being an identical image thereof;

FIG. 4 is a left side elevation view thereof (the base having the lid secured thereon), the right side elevation view being an identical image thereof;

FIG. 5 is a top plan view thereof (the base having the lid secured thereon);

FIG. 6 is a bottom plan view thereof (the base having the lid secured thereon);

FIG. 7 is an angled front exploded perspective view thereof with the lid detached from the base for clarity of illustration;

FIG. 8 is a front elevation view of the lid thereof, the rear elevation view of the lid being an identical image thereof;

FIG. 9 is a left side elevation view of the lid thereof, the right side elevation view being an identical image thereof;

FIG. 10 is a top plan view of the lid thereof;

FIG. 11 is a front elevation view of the base thereof, the rear elevation view of the base being an identical image thereof;

FIG. 12 is a left side elevation view of the base thereof, the right side elevation view of the base being an identical image thereof;

FIG. 13 is a top plan view of the base thereof; and,

FIG. 14 is a bottom plan view of the base thereof.
